UNITED STATES PATENT OFFICE.

RUSSELL A. SMITH, OF MINDEN CITY, MICHIGAN, ASSIGNOR TO R. A. SMITH MANUFACTURING CO., OF MINDEN CITY, MICHIGAN.

CUSPIDOR.

Application filed October 31, 1924. Serial No. 747,099.

This invention relates to cuspidors and has for its object the provision of a device of this character designed for use in automobiles so that the occupants may spit comfortably without craning their necks over the sides of the car, without opening any doors or windows, and also without danger of unpleasantness to the other occupants especially in windy weather.

10 An important object is the provision of a device of this character which is located in the floor of the car which includes a normally closed receptacle provided with means whereby it may be opened to permit emptying any accumulation, the cuspidor being moreover normally covered by a movable top which may be kicked or otherwise moved out of the way when use of the device is not desired.

15 An additional object is the provision of a device of this character which will be simple and inexpensive in manufacture, easy to install, convenient and sanitary in use and a general improvement in the art.

20 With the above and other objects and advantages in view the invention consists in the details to be hereinafter more fully described and claimed, and illustrated in the accompanying drawings, in which:

25 Figure 1 is a vertical section through the complete device,

Figure 2 is a section through the floor showing a side elevation of the device with the bottom swung into open position,

30 Figure 3 is a fragmentary elevation showing the bottom closed,

Figure 4 is a fragmentary section showing the catch for holding the bottom open or closed, and

35 Figure 5 is a plan view thereof.

Referring more particularly to the drawings the letter A designates the floor of an automobile in which my device is installed. In carrying out my invention I form this

40 floor A with a circular hole within which is disposed a preferably frusto conical or slightly tapered receptacle 10 having an open bottom 11 reinforced by a band 12 riveted or otherwise secured thereto. At its

45 upper edge this receptacle 10 is formed with an out-turned flange 13 which rests upon the top of the floor and which is suitably secured thereto.

50 The top of the receptacle is ordinarily closed by a disk 15 pivoted upon a bolt 16

so as to be swung into or out of obstructing relation to the receptacle. This disk is of sufficient diameter to entirely cover the flange 13 and it may be constructed of brass or any other suitable material properly treated to have a pleasing appearance. The pivot bolt 16 preferably carries a spring 17 which operates to prevent the cover from swinging too freely and to hold the cover down onto the flange 13. At some convenient point the cover disk is provided with a knob 18 which may be engaged by the fingers or kicked by the foot when it is desired to cover it after use.

55 The bottom of the receptacle is normally closed by a bottom plate 21 connected with the lower edge of the receptacle by a hinge 22 which normally tends to hold the bottom shut. The means for effecting opening of this bottom plate, when such is desired, consists of a vertical push rod 23 slidable through the floor of the car and having its upper end provided with a knob 24 and its lower end pivotally engaged within a slot 25 in a crank arm 25 carried by the bottom 60 plate 21. When pressure is applied to the knob 24 it is of course apparent that the downward movement of the push rod 23 will swing the bottom plate 21 downwardly 65 into open position.

70 In Figures 4 and 5 I have shown a catch device for holding the bottom either open or closed. In carrying out this feature the plunger 23 is formed with grooves 31 and 32 with which may be engaged the forked or slotted end 33 of a latch 34 slidable beneath a guide 35 and having an operating button 36 movable along a slot 37 in the guide. When the plunger is depressed to open the bottom the latch may be engaged with the 75 groove or flattened portion 31 to hold the bottom open and the bottom may be held shut by engaging the latch with the groove 32.

80 From the foregoing description and a study of the drawings it is believed that the construction, operation and utility will be obvious without any necessity for additional explanation. It is to be noted that the device is not at all unsightly and it is not only 85 a great convenience but may also be considered as a sanitary appliance, inasmuch as it will eliminate the pernicious practice of promiscuous expectoration.

90 While I have shown and described the 95

preferred embodiment of the invention it is of course to be understood that I reserve the right to make such changes in the form, construction and arrangement of parts as will not depart from the spirit of the invention or the scope of the subjoined claims.

Having thus described the invention, I claim:

19. 1. In a vehicle cuspidor, a casing mounted within an opening in the floor of a vehicle, both ends of the casing being open and the upper end being formed with an outstanding flange seating upon the upper surface of the floor, a movable cover normally closing the open upper end and registering therewith, a closure member for the open bottom formed as a disc fitting snugly within the open bottom and hingedly mounted at one side thereof, an arm carried by said disc and projecting upwardly therefrom at the side of the casing at an angle, said arm having an intermediate portion off-set whereby to clear the side of the casing, the terminal portion of the arm being provided

with an elongated slot, a push rod slidably mounted through the floor and having its lower end carrying a pin slidably and pivotally engaged within said slot, means normally tending to urge the push rod upwardly, and a latch device mounted upon the floor and adapted to be moved into engagement with the push rod for maintaining said closure disc selectively in open or closed position.

2. In a device of the character described, including a casing mounted within an opening through a floor, a hinged closure member for the casing, and a push rod pivotally connected with the closure member for operating the same, retaining means for holding the push rod in a selected position with said closure member either open or closed, comprising a guide mounted upon the floor, a latch device slidably mounted within said guide and having a forked end, said push rod being provided with a pair of grooves selectively engageable by said fork.

In testimony whereof I affix my signature.

RUSSELL A. SMITH.
